US00D843674S

(12) **United States Design Patent** (10) **Patent No.:** **US D843,674 S**
Buckley et al. (45) **Date of Patent:** **** Mar. 19, 2019**

(54) **HARD SURFACE CLEANING DEVICE**(71) Applicant: **Unger Marketing International, LLC**,
Bridgeport, CT (US)(72) Inventors: **James M. Buckley**, New Hartford, CT
(US); **Joseph K. Patterson**, Monroe,
CT (US)(73) Assignee: **UNGER MARKETING
INTERNATIONAL, LLC**, Bridgeport,
CT (US)(**) Term: **15 Years**(21) Appl. No.: **29/616,959**(22) Filed: **Sep. 11, 2017****Related U.S. Application Data**(63) Continuation of application No. 29/577,653, filed on
Sep. 14, 2016.(51) **LOC (11) Cl.** ..... **07-05**(52) **U.S. Cl.**USPC ..... **D32/70**(58) **Field of Classification Search**USPC D32/71, 73, 72, 70, 69, 68, 35; D8/71,

Primary Examiner — Austin Murphy(74) *Attorney, Agent, or Firm* — Cantor Colburn LLP(57) **CLAIM**The ornamental design for a hard surface cleaning device, as
shown and described.**DESCRIPTION**FIG. 1 is a front, top perspective view of a hard surface
cleaning device according to the present disclosure;FIG. 2 is a rear, top perspective view of the hard surface
cleaning device of FIG. 1;FIG. 3 is a first side view of the hard surface cleaning device
of FIG. 1;FIG. 4 is a second, opposite side view of the hard surface
cleaning device of FIG. 1;FIG. 5 is a front view of the hard surface cleaning device of
FIG. 1;FIG. 6 is a rear view of the hard surface cleaning device of
FIG. 1;FIG. 7 is a top view of the hard surface cleaning device of
FIGS. 1; and,FIG. 8 is a bottom view of the hard surface cleaning device
of FIG. 1.The broken lines in the figures form no part of the claimed
design.**1 Claim, 8 Drawing Sheets**| (56)	References Cited
